UNITED STATES PATENT OFFICE.

WILLIAM D. JAMES, OF WALES, WISCONSIN.

COMBINED CATTLE STALL AND MANGER.

No. 899,829.

Specification of Letters Patent.

Patented Sept. 29, 1908.

Application filed September 19, 1906. Serial No. 335,164.

To all whom it may concern:

Be it known that I, WILLIAM D. JAMES, a citizen of the United States, residing at Wales, State of Wisconsin, have invented 5 new and useful Improvements in a Combined Cattle Stall and Manger, of which the following is a specification.

My invention relates to improvements in a combined manger and stall for cattle.

10 The object of my invention is among other things to provide a manger that is not only more sanitary than those heretofore used but which when not in use may be raised and thrown back out of the way thereby economizing space; and when thus thrown back the front board of the manger will form a hood above the cattle's heads and shield them from contact with falling chaff and other refuse matter from the fodder above, and a 15 further object of my invention is to provide a manger which is more readily cleaned of refuse matter than those heretofore made for which reason it is more sanitary.

The construction of my invention is explained by reference to the accompanying drawings in which,

Figure 1 is a perspective view showing the manger in its normal position for use. Fig. 2 is a perspective view showing the manger in 25 its raised position.

Like parts are identified by the same reference characters in both views.

1 represents the manger which is pivotally suspended from the vertical post 2 by a plurality of links 3 and a plurality of pivots, said links 3 being connected at one end with the post 2 by pivotal bolts 4 and at their opposite ends with the manger 1 by the pivotal bolts 5. The manger comprises the diagonal front 30 board 6, end boards 7, 7, and a plurality of partitions 8, whereby said manger is subdivided into as many compartments by said partitions as there are stanchions 9. The stanchions 9 are of the ordinary construction 35 and are supported at their lower ends from the floor upon the horizontal bar 10, while their upper ends are pivotally connected with the horizontal bar 11, said bars, 10 and 11, being connected at their respective ends 40 and at intervals with the post 2, in the ordinary manner. The manger 1 is preferably open at the bottom, whereby the feed placed therein is permitted to rest upon the floor, and whereby when the manger is raised from 45 the position shown in Fig. 1 to that shown in

Fig. 2 all feed or refuse material therein will drop freely therefrom and remain upon the floor when it can be readily swept away. The manger is raised from the position shown in Fig. 1 to that shown in Fig. 2 by the winding shaft 12 which is operated by the crank 13. Motion is communicated from the shaft 12 to the manger 1 by the flexible connections 14, cord chain or wire cable being used for such flexible connection.

In constructing my manger I preferably form several compartments in connection with the single front board 6, whereby all of said compartments will be simultaneously raised by turning the winding shaft 12. The 60 lower end of the flexible connection 14 is connected with the upper edge of the manger and its upper end is connected with said winding shaft, whereby as the crank 13 is turned the upper end of said flexible connection will be wound on the shaft and the manger will be raised as stated from the position shown in Fig. 1 to that shown in Fig. 2, when the manger can be retained in that position by throwing the crank retaining lug 15 from 65 the vertical position shown in Fig. 1 to the horizontal position shown in Fig. 2 in front of the crank 13 whereby said crank will be prevented from turning and said flexible connection from being unwound from the shaft. 70 When, however, it is desirous to lower the manger said retaining lug 15 will be disengaged from the crank when said crank will be revolved in the opposite direction thus permitting the manger to fall back to its normal 75 position shown in Fig. 1 when the manger is ready for use.

The space in the rear of the several compartments of the manger is subdivided into a plurality of stalls by a plurality of metallic 80 partition frames 16, which are preferably made of tubing and connected at their upper ends with the post 2 and at their lower ends with the floor 17 by ordinary pipe fittings in the usual manner, when it is obvious that 85 said metallic partition frames perform the two-fold functions of subdividing the space in the rear of the manger into stalls and also as post supporting braces by which said post 2 and the bars 10 and 11 connected therewith are rigidly retained in their proper position.

In the preferred form of stall, shown in Fig. 1, I preferably employ an additional horizontal bar 18 which bar is connected at 90

its front end to the metallic post 19 by ordinary pipe fittings 20 and at its rear end to the vertical post 2, said bar 18 not only serves to strengthen and support the stall but prevents the liability of cattle getting through the same.

While I have shown my improved form of manger connected with a stanchion supporting frame, comprising a plurality of vertical posts 2 connected together by horizontal bars, it is obvious that said stanchions do not form a material part of my present invention and may be dispensed with or substituted by vertical posts. The essence of my invention 10 consists in providing means for pivotally supporting the manger in such manner that it may be raised when not in use from position shown in Fig. 1 to that shown in Fig. 2 regardless of the means of securing the cattle in 15 place in rear of said manger; and in the metallic partition frame by which said posts are supported.

Having thus described my invention what I claim as new and desire to secure by Letters 25. Patent is,

1. In a device of the described class the combination of a plurality of vertical posts, a manger, a plurality of manger supporting links, means for pivotally connecting said 30 links at one end to said manger and additional means for pivotally connecting said links at their opposite ends to said posts, means for raising said manger from its normal position, and means for securing said 35 manger in its raised position the pivotal connections of said mangers with said links being adapted to permit the mouth of said mangers to be brought to the vertical in close contact with the vertical supporting 40 posts.

2. In a device of the described class the combination of a stanchion supporting frame, a plurality of stanchions supported in said frame, a manger located in front of said 45 stanchions, a plurality of manger supporting links, means for pivotally connecting said links at one of their ends to said frame and additional means for connecting said links at their opposite ends to said manger, means 50 for raising said manger, and means for securing said manger in its raised position with

its mouth against the vertical side of said frame.

3. In a device of the described class the combination of a stanchion supporting frame, a manger subdivided by a plurality of vertical partitions into a plurality of separate compartments open at their lower and rear sides, adapted when raised to deposit its remaining contents upon the floor, a plurality of manger supporting links, pivotal bolts connecting said links at one end to said manger and their opposite ends to said frame, means for simultaneously inverting and raising all of said compartments from 55 their normal to their elevated position and means for securing the same when raised in such elevated position.

4. In a device of the described class the combination of a stanchion supporting frame comprising a plurality of vertical posts and horizontal bars, a plurality of stanchions pivotally connected at their upper and lower ends to the upper and lower bars of said frame, a plurality of stall partition frames 70 connected at one end to one side of said vertical posts and at their opposite ends with the post supporting floor, said frames being adapted to serve the two-fold purpose of partitions between the respective stanchions 75 and of braces for the stanchion supporting frame, a manger open at the bottom and one side a plurality of manger supporting links pivotally connected at one end to said manger and at their opposite ends to said posts 80 upon the opposite side from said partition frame, a winding shaft extending longitudinally of said frame and revolvably connected therewith, flexible connections communicating directly between said winding shaft 85 and the upper edge of said manger, and adapted to be wound upon said shaft, a crank for revolving said winding shaft and means for retaining said manger when raised in its elevated position, all substantially as 90 and for the purpose specified:

In testimony whereof I affix my signature in the presence of two witnesses.

WILLIAM D. JAMES.
